Primary Examiner — Keli L Hill*Assistant Examiner* — Harold E Blackwell, II(74) *Attorney, Agent, or Firm* — Bradley J. Thorson**CLAIM**

We claim the ornamental design for casement window operator cover and folding handle, as shown.

DESCRIPTION

FIG. 1 is a left isometric view of a casement window operator cover and folding handle;

FIG. 2 is right isometric view of the casement window operator cover and folding handle depicted in FIG. 1;

FIG. 3 is a left elevation view of the casement window operator cover and folding handle depicted in FIG. 1;

FIG. 4 is a right elevation view of the casement window operator cover and folding handle depicted in FIG. 1;

FIG. 5 is a top plan view of the casement window operator cover and folding handle depicted in FIG. 1; and,

FIG. 6 is a front elevation view of the casement window operator cover and folding handle depicted in FIG. 1.
